BAR TOOL OR SIMILAR ARTICLE

Vincent S. Belpedio, Fairfield, Conn., and Gottfried Fred Stern, Saugerties, N. Y., assignors to Bellern Research Corp., Saugerties, N. Y., a corporation of New York

Application December 21, 1953, Serial No. 28,150

Term of patent 14 years

(Cl. D44—29)

Fig. 1.

Fig. 2.

Fig. 3.

Fig. 4.

To all whom it may concern:

Be it known that we, Vincent S. Belpedio and Gottfried Fred Stern, citizens of the United States and residents, respectively, of Fairfield, Connecticut, and Saugerties, New York, have invented a new, original, and ornamental Design for a Bar Tool or Similar Article, of which the following is a specification, reference being had to the accompanying drawings, forming part thereof.

In the drawings:

Fig. 1 is a perspective view of a bar tool or similar article, showing our new design;

Fig. 2 is a top plan view thereof;

Fig. 3 is a bottom plan view thereof; and

Fig. 4 is a side elevational view thereof.

The dominant features of our design are shown in full lines.

We claim:

The ornamental design for a bar tool or similar article, substantially as shown and described.
